UNITED STATES PATENT OFFICE.

FRANK B. WHITCOMB, OF SAN FRANCISCO, CALIFORNIA.

KEY TAG.

Application filed June 27, 1923. Serial No. 648,042.

To all whom it may concern:

Be it known that I, FRANK B. WHITCOMB, a citizen of the United States, residing at San Francisco, in the county of San Francisco and State of California, have invented new and useful Improvements in Key Tags, of which the following is a specification.

This invention relates to improvements in key tags such as are used in hotels.

10 Key tags of the type now universally employed are flat and bear room numbers on one or both flat faces. When these tags are deposited in the built up tiers or rows of boxes or pigeon holes such as are now used 15 in hotels, the numbers on the tag cannot be read unless the tags are removed and the clerk must reach into the boxes of the upper rows to ascertain whether or not keys are contained therein. Often a letter, pack- 20 age or other article placed in a box will conceal the key tag therein and this necessitates the removal of the letter or other object to get at the key, or would give the impression that the key is "out" of the box.

25 Keys and tags are frequently misplaced in the boxes or carried off by guests of a hotel, or left in the rooms. To locate a misplaced or "lost" key, many of the keys in the boxes and often all of them, must be 30 removed in order to locate the misplaced or lost key. A search of this nature is troublesome and time consuming. The proper 35 depositing of the keys of hotel rooms in the boxes provided therefor is highly essential to efficient management of a hotel but as hereinbefore pointed out, the keys are often not handled properly and a great deal of inconvenience and loss of time is experienced.

The primary object of this invention is 40 to provide a key tag which will eliminate the difficulties and objections such as have been heretofore occasioned in the handling of hotel keys and I accomplish this end by the provision of a projector or up- 45 standing portion on a key tag body of the ordinary flat type, which upstanding portion or projection bears the room number and presents the same so that it will always be readily visible when the tag is deposited 50 in a box regardless of the placing of letters or other objects in the box.

Another object of the invention is to provide in a tag of the character described, means for removably holding a number plate

or slip on the upstanding portion or projection whereby the changing of the number plate may be readily effected.

Another object is to provide on the tag means for holding a card, memo or signal slip, tag, note or letter, in upright and readily visible position.

Another object is to provide a tag of the character described which provides for use of interchangeable advertising cards or matter.

Another use of the tag of the invention is that the upstanding portion or projection will act as a support or rest for a card or letter placed between one side wall of the box and said upstanding portion.

A further use of the tag is that a long object, letter, or magazine, or newspaper such as would ordinarily be subject to readily falling out of a box, when inserted so that it lies upon the upstanding portion of the tag, will be inclined or tipped to a position insuring its remaining in place in the box.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 is a fragmentary perspective view of a box showing the tag of my invention therein.

Fig. 2 is a top plan view of the tag.

Fig. 3 is a side elevation of the tag showing a rolled newspaper as held in place in a box by the tag.

Fig. 4 is a front elevation of the number slip holder.

In the drawings, 1 designates a box of a tier of such boxes as used in hotels, 2 a key, 3 a letter in the box and 4 the tag of my invention.

The tag comprises a flat body portion 5 of any suitable material having at one end an eye 6 to provide for attachment of the key to the tag. At the other end of the

tag is a right angularly extending projection or upstanding portion 7 which preferably extends across said end and is about one inch in height although the height may be varied as desired. This portion may be a separate piece or integral with the body and although I show it to be curved or convex on its front face and with a straight rear face, said faces may be otherwise shaped if desired, since the main point is to provide for the presentation of the room or key number in an upright and readily discernible position.

One way of presenting the numbers is to provide for the use of removable number tags 8, which are removably held on the member 7 by a frame or holder 9 which latter may be secured in any suitable manner to said member. By providing long tongues 10 on the holder, the said tongues may be bent around the ends of the member 7 and serve as a clip for a note, card or letter as well as secure the holder in place. A card or letter held by the tongues would be maintained in upright position and be readily visible in any of the boxes of a tier or set.

The upstanding member on the body portion bearing the room number, in a like position, provides for a more ready reading of the number and the unusual shape of the tag is such that when handling the tag in order to return it to the box bearing the corresponding number, the clerk or attendant is more apt to exercise care in placing the tag and key than with the ordinary plate type of tag such as now used. If a key and tag is placed in the wrong box, the fact that the number is always visible to the clerk, permits the clerk to readily determine that a mistake has been made without having to pull out a great number or all of the keys in order to locate the misplaced one as now required with the old type of key tag.

As shown in Fig. 1, when a letter or card is placed in the box between the tag and one wall of the box, it is held upright and will not fall into a position lying flat in the box and escape notice. When a newspaper or magazine or a long letter or object such as are maintained in the box with difficulty, is placed so that it rests upon the tag, the upstanding portion will tilt the magazine or the long object so that it is in a position which insures its remaining in the box as shown in Fig. 3. In this connection the upstanding member will prevent concealing of

the tag by placing letters and other objects on top of it.

The body of the tag may be provided with a dovetailed recess shown at 11, in which may be removably mounted a plate or slip 12 bearing advertising matter. The other available portions of the tag may be used for bearing identification or advertising indicia as is the practice with the present style of key tags.

It will be seen with reference to the foregoing description and the accompanying drawings, that I have provided a key tag which, although very similar in appearance and size to the ordinary flat type of key tag and but slightly changed as to construction, will eliminate all of the objections and disadvantages which attend the use of the ordinary flat type of key tag and at the same time provide features of advantage not possible with the old type of tag.

The tag of this invention is more cumbersome than the ordinary flat tag and for this reason discourages the carrying of the tag in the pocket. The upstanding portion also serves as a finger piece or handle in placing and removing the tag.

I claim:

1. A key tag comprising a body portion constructed to provide an upright face of sufficient area for presenting in upright position, identifying indicia.

2. A key tag comprising a body portion having a right angularly projecting portion thereon, to one face of which right angularly projecting portion an identifying character is applied.

3. A key tag comprising a body portion, an upright member on the body portion, a holder on the upright member and an indicia bearing slip removably mounted in the holder.

4. A key tag comprising a body portion, an upstanding member on the body portion, means associated with the upstanding member for holding a card or like object in upright position, said upstanding member bearing identifying indicia in upright position thereon.

5. A key tag comprising a body portion having an upstanding portion thereon on one face of which upstanding member are applied identifying indicia and means on the opposite side of said member for supporting in upstanding position a card or similar article.

FRANK B. WHITCOMB.
